UNITED STATES PATENT OFFICE.

GEORGE JACKSON, OF BOSCOBEL, WISCONSIN.

HARROW.

SPECIFICATION forming part of Letters Patent No. 254,017, dated February 21, 1882.

Application filed December 10, 1881. (No model.)

To all whom it may concern:

Be it known that I, GEO. JACKSON, of Bos-
cobel, in the county of Grant and State of Wis-
consin, have invented certain new and useful
5 Improvements in Harrows; and I do hereby
declare the following to be a full, clear, and
exact description of the invention, such as will
enable others skilled in the art to which it per-
tains to make and use it, reference being had
10 to the accompanying drawings, which form
part of this specification.

My invention relates to an improvement in
harrows; and it consists in the combination of
15 four sections, each one of which is composed
of a number of parallel beams which are placed
equal distances apart, and which are united to-
gether by means of rods which pass diagonally
through the ends of adjoining sections, the
20 beams being so arranged that the ends of no
two of the beams will come together, as will be
more fully described hereinafter.

The object of my invention is to provide a
harrow which can be turned up from any one
25 corner, and which is adapted to be pulled
from any one corner or side equally as well,
without the necessity of any changes, with
the exception of the device to which the draft-
chains are to be fastened.

Figure 1 is a plan view of my invention,
30 partly in section. Fig. 2 is an edge view of the
same, showing one-half of the harrow turned
up at one corner.

A represents four separate and distinct sec-
tions of the harrow, each one of which is formed
35 of the three beams B, which are placed equal
distances apart. The beams of any one sec-
tion are made the same length as the corre-
sponding section which is made opposite to it,
and in which case the beams are secured rig-
40 idly together by means of the brace-rods D,
which are secured across their tops. These
four sections are attached loosely together by
means of the pivotal rods E, which are passed
diagonally through their corners, each rod
45 passing at an angle through the end of each
beam of both sections. The outer ends of
these rods are hooked or bent backward in any
suitable manner, and the inner ends of the
rods are passed through washers or shoes H,
50 which are made of iron and secured to the in-
ner beams of the two sections which have the
shortest inner beams. In order to prevent the
inner ends of the rods from being pulled out-

ward through the washer, pins or stops of any
kind may be applied to the rods, as shown. 55

Each corner of the harrow will be provided
with two holes—one in each adjoining section—
in which suitable staples or holding-bolts
will be placed, and to these staples or bolts
60 will be fastened a suitable draft-chain. This
draft-chain can be transferred from one corner
to the other of the harrow, and thus enable the
harrow to be drawn equally well from each one
of its four corners.

As the pivotal rods pass loosely through the 65
ends of the beams of each section these rods
form a pivot upon which any two of the sec-
tions can be raised upward from any one of its
four corners, as shown in Fig. 2.

It will be noticed that the beams are ar- 70
ranged in such relation to each other that the
end of no one beam comes in contact with the
end of another beam, but that the ends are all
placed at equal distances apart, as shown, so
that the pivotal rods will pass through the 75
end of each beam alike. While the ends of
these beams do not come together, the end of
each beam bears against the edge of another
beam, and the parts are thus braced together
80 while in operation without in any manner in-
terfering with their folding movement.

As the harrow is drawn along, in case an
obstruction is encountered the harrow will
give equally alike at any point. Should the
obstruction be just in a line with the center of 85
the harrow the harrow will rise upward at the
center, so as to pass over it; but should the
obstruction be to either side of the center the
outer corners of the harrow will rise upward.

This same construction of parts can be ap- 90
plied to a single V or A shaped harrow.

Having thus described my invention, I
claim—

In a harrow, the combination of a number of
95 sections, A, each one of which is composed of
a number of beams or bars, B, of unequal length,
with the pivotal rods E, which pass diagonally
through the ends of the beams, substantially
as shown.

In testimony whereof I affix my signature in 100
presence of two witnesses.

GEORGE JACKSON.
